STOP WATCH

Henri Hofer, Geneva, Switzerland, assignor to
firm Fabrique D'Ebauches Venus S. A., Moutier,
Switzerland

Application December 26, 1934, Serial No. 759,305
In Switzerland January 25, 1934

2 Claims. (Cl. 58—76)

This invention relates to stop watches of the type having a chronograph wheel which drives a seconds indicating hand, and a counter wheel which indicates the number of revolutions made by the chronograph wheel.

Usually in such types of stop watches provision is made of a pillar wheel to which a step by step movement can be imparted and which controls a rocking lever carrying a driving wheel imparting rotation to the chronograph wheel. By actuating the pillar wheel, by means of a push rod, said lever can be made to rock so as to engage the driving wheel with the chronograph wheel or to disengage it therefrom.

In the present invention the wheel which imparts rotation to the chronograph wheel is mounted on an arbor of the normal time train of the watch, which arbor is fulcrumed at one of its ends and engaged in the rocking lever at the other end. In this manner it is possible to disengage the chronograph wheel from driving engagement by making said arbor swing slightly about its fulcrum, so that the wheel coacting with the chronograph wheel falls out of mesh with this chronograph wheel, while the wheels on this arbor which belong to the normal time train remain in driving engagement with the corresponding wheels of the time train.

It is an object of this invention to provide means for permitting said arbor to swing in a transverse plane but preventing any substantial axial movement of the arbor, independently of the fact that this arbor is engaged in the rocking lever controlled by the pillar wheel, so that when for any reason the stopping and counting mechanism must be removed from the watch movement, said arbor remains in its proper position with respect to the time train and to permit removal of the rocking lever without that the arbor must be removed and the wheels of the time train run completely down.

In the accompanying drawing, showing a preferred form of embodiment of the invention,

Figure 1 is a plan view of a stop watch movement according to the invention.

Figure 2 is a section taken along the line 2—2 of Figure 1 and drawn to a larger scale.

The watch movement shown in Fig. 1 is actuated by a main spring lodged in the spring barrel 1 on the axis 2 of which is mounted a gear wheel 3 frictionally engaging with the barrel 1 and meshing with the cannon pinion 4 connected by minute wheels 5 to the hour wheel 6 which carries the hour hand. It will be seen that

minute and hour hands are actuated as in usual "Roskopf" watch movements.

The gearing of the spring barrel 1 meshes with a pinion 7 rigid with a gear wheel 8 which is in mesh with the pinion 9 of the seconds wheel 10 engaging the pinion 11 of the escape wheel 12. The stem 13 permits winding of the main spring and setting of the watch.

A pillar wheel 15 coacts with a push rod 16 slidably mounted in a slot 17 of the movement plate 18. A spring 19 urges the push rod outwardly which rod, when a push is exerted thereon with the finger makes the pillar wheel turn through one tooth. A finely toothed chronograph wheel 20 is disposed as usual in the center of the movement and is rigid with a heart 21 and with a finger 22. The counter wheel 23 is rigid with the hand indicating the number of revolutions of the chronograph wheel, and with a heart 24. The two hearts 21 and 24 coact with a hammer 25 the position of which is controlled by the pillar wheel 15.

A rocking lever 26 is pivoted on the movement plate at 27 and its position is also controlled by the pillar wheel 15. The rocking lever 26 carries an intermediate gear wheel 28 meshing with the counter wheel 23 and coacting with the finger 22 which imparts a slight movement of rotation to the wheel 28 at each complete revolution of the chronograph wheel 20. The arbor 29 of the seconds wheel 10 has one end carried by a bridge 30 and the other end by the rocking lever 26. A finely toothed wheel 31 is rigidly mounted on this shaft near that end thereof which is engaged in the rocking lever. According to the position of the rocking lever, this wheel 31 can be brought in driving engagement with the chronograph wheel 20.

The arbor 29 is provided with a collar 32 intermediate the two wheels 30 and 31, and disposed within an opening 33 of the movement plate. This opening is closed by a plate 34 screwed to the movement plate and provided with an opening 35 for the passage of the arbor 29. This opening 35 has a slightly larger diameter than the arbor, so as to permit a small lateral to-and-fro movement of this arbor corresponding to a slight rocking movement of the lever 26. A spring 36 tends to turn the lever 26 in counterclockwise direction to maintain the wheel 31 in engagement with the center wheel 20. An eccentric screw 37 screwing into the movement plate permits exact adjustment of the position of the lever 26 so that it properly coacts with the pillar wheel 15.

As it is usually the case in stop watches, the described mechanism can occupy three positions, the first in which the counting mechanism is running, the second in which the mechanism is stopped, and the third in which the wheels are set back to zero position.

The first of these positions is shown in Fig. 1 of the drawing. The free end of the lever 26 penetrates between two pillars of the pillar wheel 15 and the wheels 31 and 20 mesh with each other, the wheel 31 being actuated by the main spring and imparting to the wheel 20 one revolution per minute. After each revolution of this wheel the finger 22 actuates the wheel 28 which turns the wheel 23 through one tooth. A spring 38 yieldingly holds this wheel in its position.

When now a push is exerted on the push rod 16, the pillar wheel 15 turns through a short distance and the lever 26 penetrating in the path of the pillars of the wheel 15, is pushed in clockwise direction by one of the pillars and then maintained on top of one of the pillars. Owing to this movement of the lever 26 the wheel 31 has disengaged from the wheel 20, since the bearing for the arbor 29 in the lever 26 has moved with the lever, this movement being permitted by the opening 35 in the plate 34; also the wheel 28 has moved out of the path of the finger 22. The hammer 25 which in the first position had its edge 39 engaged on top of a pillar of the wheel 15, is still maintained in this position after the first push on the rod 16, since the wheel 15 has not turned far enough to make the edge 39 fall off the pillar. After a second push on the rod 16 the hammer 25 however falls off the pillar and the spring 40 makes the hammer turn about its pivot 41 to have the two flat edges 42 and 43 act against the hearts 21 and 24, respectively, so that these hearts are urged into a position corresponding to the zero position of the wheels 20 and 23, respectively. After the second push on the rod 16 the free end of the lever 26 is still engaged on top of a pillar to maintain the wheel 31 separated from the center wheel 20, while after a third push, the mechanism is again in running position as represented in Fig. 1.

The plate 35 and the collar 32 on the arbor 29 have the purpose to limit the longitudinal movements of the arbor 29. Owing to this disposition the arbor 29 always keeps its proper position relative to the other members of the wheelwork, even when the rocking lever 26 is removed. When the mechanism is assembled, it is possible to place the arbor 29 in its position before the lever 26 is added, and when any repair work has to be done, the lever can be removed while the arbor remains in its position.

I claim:

1. A spring driven stop watch having a chronograph wheel, a counter wheel indicating the number of revolutions of the chronograph

wheel, a driving finger rigid with the chronograph wheel, an intermediate wheel meshing with said counter wheel and actuated by said driving finger, a wheelwork transmitting movement from the driving spring to the chronograph wheel, one of the wheels of said wheelwork being movable into and out of engagement with the chronograph wheel, a rocking lever carrying said intermediate wheel, a fulcrumed arbor carrying said movable wheel of the wheelwork and having one end journaled in said rocking lever, said rocking lever being movable into one or the other of two positions, an apertured plate traversed by said arbor and disposed intermediate the rocking lever and the fulcrum of the arbor, a collar on said arbor coacting with said plate for preventing substantial axial movement of the arbor but permitting transverse movement thereof, a pillar wheel coacting with said rocking lever, and means for imparting a step by step movement to said pillar wheel to move said rocking lever into one or the other of its two positions, whereby in one position of the lever said movable wheel engages the chronograph wheel and said intermediate wheel projects into the path of said driving finger, whilst in the other position said movable wheel and said intermediate wheel are removed from the chronograph wheel and from the driving finger, respectively.

2. A spring driven stop watch having a chronograph wheel, a counterwheel indicating the number of revolutions of the chronograph wheel, an intermediate wheel transmitting movement from said chronograph wheel to the counterwheel, a wheelwork transmitting movement from the driving spring to the chronograph wheel, one of the wheels of said wheelwork being movable into and out of driving engagement with the chronograph wheel, a rocking lever carrying said intermediate wheel, a fulcrumed arbor carrying said movable wheel of the wheelwork and having one end journaled in said rocking lever, a collar on said arbor, abutment means coacting with said collar to prevent substantial axial movement of the arbor but permitting a limited transverse movement thereof, a pillar wheel coacting with said rocking lever, and means for imparting a step by step movement to said pillar wheel to move said rocking lever into one or the other of two positions, whereby in one position of the lever said movable wheel engages the chronograph wheel and said intermediate wheel transmits rotation from the chronograph wheel to the counterwheel, whilst in the other position said movable wheel and said intermediate wheel are removed from driving relation with the chronograph wheel.

HENRI HOFER.
